UNITED STATES PATENT OFFICE.

WILLIAM I. STILWELL, OF MANSFIELD, OHIO, ASSIGNOR OF ONE-HALF TO
GEORGE B. SOLDERS, OF CLEVELAND, OHIO.

CASTER.

SPECIFICATION forming part of Letters Patent No. 640,499, dated January 2, 1900.

Application filed March 23, 1899. Serial No. 710,150. (No model.)

To all whom it may concern:

Be it known that I, WILLIAM I. STILWELL, a citizen of the United States, residing at Mansfield, in the county of Richland and State 5 of Ohio, have invented certain new and useful Improvements in Antifriction Roller-Casters; and I do declare that the following is a full, clear, and exact description of the invention, which will enable others skilled in the art to 10 which it appertains to make and use the same.

My invention relates to antifriction roller-casters; and the especial object of the invention is to provide a caster which will meet the needs of pianos, bookcases, safes, and 15 other heavy articles of furniture, which articles by reason of their very great weight are difficult to handle.

The invention therefore consists in a roller-caster constructed and adapted to operate substantially as shown and described, and particularly pointed out in the claim.

In the accompanying drawings, Figure 1 is a sectional elevation of my improved caster, showing the socket and hub in sectional elevation. Fig. 2 is a plain elevation of the upper part of the wheel-frame and its spindle, with the wheel partly in section, as herein-after fully described.

The invention as thus shown is designed to 30 occupy a place in this art which, so far as I can ascertain, has not been satisfactorily met by any or all of the heavy-weight casters heretofore known.

In heavy furniture of the kind hereinbefore mentioned the excessive continued pressure which comes on the caster when in a state of rest and from which there is no relief is such as to put any construction to very severe trial, and experience has demonstrated 40 that very few casters are able to withstand it and at the same time be ever ready to move easily with their heavy load. I have found, for example, that the firmest woods under excessive pressure will give way sooner or 45 later and that a quality of roller or principle of construction admirably adapted for ordinary house furniture is wholly unsuitable to the needs of heavy articles. I have also found that antifriction-balls about a roller-spindle 50 are wholly unsuited to heavy furniture, because they will cut grooves in their bearings

and leave a large part of the spindle unprotected. In view, therefore, of all that has been done to meet the needs of this art for heavy work it still remains true that there is 55 demand for a caster which combines the elements of strength and durability and ease of operation and which is not too expensive to make or purchase.

Referring now again to the drawings, A 60 represents a tubular socket adapted to be set into the furniture-leg or other portion of the furniture prepared for the purpose and has a flange *a* about its bottom, through which are passed screws for fastening the socket in 65 place. Internally this part A has a fairly large uniform bore extending practically the full depth and which may be referred to as the spindle "socket" or "bearing," and in the top of the socket, which is closed, is a 70 small pointed cavity *a'* for the point of the spindle. The said frame B has several portions essential to its completeness, consisting of the yoke 2, in which the wheel or roller C is supported, the hub 3, and the spindle 4. 75 Both the hub 3 and the socket-base are of peculiar and novel construction, adapting the caster to carry a series of horizontally-arranged antifriction-balls, which are the exclusive weight-bearers between the socket A 80 and the wheel-frame B and which yet are adapted to take all the lateral bearing and friction, as occurs when the furniture is moved and the caster whips around one way or another to bring it in line with the direction of movement. A prompt response of the caster at this time is always desirable, but in heavy furniture it is absolutely indispensable, as otherwise the furniture cannot be moved and bestowed as may be desired. To these several ends the hub of the frame B has a raised circular portion or pedestal *b*, with a groove or channel in its top around the spindle 4, and the antifriction-balls D rest in this groove. The complement 90 of the pedestal *b* is formed in the base of the socket A, in which is a cavity bordered in part by the stock of the socket and by the depending flange *c*, which overlaps the pedestal *b*, and while it is apart therefrom to prevent 95 friction is yet near enough to perform service in emergencies when the furniture is moved 100

and possibly excessive lateral strain comes on the caster. Then the surfaces of the overlapping portions *b* and *6* will contact and support the caster to the utmost that may be needed. Ordinarily, however, the balls *D* perform their complete dual office of horizontal and vertical antifriction-bearings. The socket-cavity has a corresponding annular channel to that in the hub for the balls *D*, and the circles of these opposite channels practically meet on both sides, thus forming together a substantially cylindrical circular channel.

It is designed that all vertical and lateral strain shall be borne by the balls *D*, as already described, and hence the spindle *4* is intended to be relieved of all such strain at all other points, and its extremity is reduced to a taper, with a point *7* to enter cavity *a'*, simply to steady it laterally, but not to carry any weight. A retaining pin or plug *8* enters a groove *9* about the neck of the spindle, and the same purpose as is served by the reduced end *7* might be served if, say, three such pins as *8* were introduced in triangular relation to provide lateral support at the top of the spindle. This or any equivalent steadyng means may be used, the more essential part of the invention being in the structure involving the balls *D*.

Preferably cylindrical antifriction-rollers *E* are used in the wheel *C*, and a wheel with a broad nearly-flat tread also is preferred and also preferably of metal, so as to stand any

weight without injury or danger of being 35 crushed.

What I claim as new, and desire to secure by Letters Patent, is—

In a caster, the wheel-frame composed of a roller-supporting yoke, a hub *3* having a raised 40 circular pedestal, *b*, in the top of which is formed an annular ball-channel, and a vertical spindle *4*, made integral with the pedestal, rising therefrom, and terminating in a pointed head *7* and a neck *9*, in combination with a 45 tubular closed cap-socket, *A*, covering and inclosing said pedestal and spindle, and provided with a cavity, *a'*, as a seat for the point 50 of said spindle, said socket also provided with a laterally-extending flange *a*, for securing the socket to the article, and with an inner depending flange, *6*, extending below the said flange, *a*, and overlapping the pedestal, *b*, said socket also formed with an annular 55 ball-channel, complementary to the said pedestal-channel, balls in said channels, and a pin in the socket adapted to enter the neck of the spindle to steady it, whereby all vertical and lateral strain from the supported article is borne by said balls, and their support, substantially as described.

Witness my hand to the foregoing specification this 15th day of March, 1899.

WILLIAM I. STILWELL.
